6 Claims. (Cl. 280—11.13)

1

The present invention relates to improved ski construction. It is an object of the invention to provide skis which have greater resilience without, however, decreasing their strength. A feature of the construction in accordance with the invention is that it not only materially increases the resilience of the ski as a whole but provides a better distribution or "balance" of resiliency throughout the length of the ski.

In accordance with the invention, the ski is built up to the desired thickness from two or more layers or pieces of material, at least one of which is provided in the median portion of its length with a series of transverse grooves or recesses which face the adjacent layer of material and are closed at their ends so as to form completely closed cavities when the layers are secured together, for example by gluing. These cavities give the median portion of the ski greater resilience. Preferably, the central cavities are larger and the cavities towards the ends of the series are progressively smaller, so that the resilience is graduated. It is also preferred to provide spaced elongated channels extending lengthwise of the ski, forwardly and rearwardly of the aforementioned series of transverse cavities, and to embed resilient metallic strips in these channels. The closed cavities in the median portion of the ski cooperate with these resilient metallic strips extending forwardly and rearwardly from the cavities to provide correctly proportioned resiliency of the ski throughout its length.

The invention will be more fully understood from the following description in conjunction with the accompanying drawings which show, by way of example, a preferred embodiment of the invention.

In the drawings:

Fig. 1 is a side elevation of an entire ski in accordance with the present invention.

Fig. 2 is a plan view of the ski.

Fig. 3 is an enlarged sectional view taken along the lines 3—3 of Fig. 4 of the median section of the ski.

Fig. 4 is a cross-section along the line 4—4 in Fig. 3.

Fig. 5 is a cross-section along the line 5—5 in Fig. 4.

Fig. 6 is an enlarged cross-section along the line 6—6 in Fig. 2.

The ski shown in the drawings is built up to the desired thickness from a plurality of layers or pieces of wood cemented together. As shown in the drawings, there are three layers, com-

prising an upper layer 1, an intermediate layer 2 and a lower layer 3. Each layer is in turn formed of a plurality of slats which are placed side by side and cemented together. The lower layer 3 has its bottom surface covered with a protecting covering 4 of plastic material.

In the median portion of the length of the ski, the upper layer 1 is provided with a thicker portion 5 which is adapted to receive the binding for attaching the ski to the skier's foot. In the lower face of this median portion, there are provided a series of grooves 6. These grooves are formed only in the central slat or slats which form the upper layer or piece 1 (Figs. 3 and 5) and do not extend through the outer slats constituting the edges of the ski. The outer slats thus close the ends of the grooves or recesses 6 so that when the layers 1 and 2 are cemented together, the recesses 6 form completely enclosed cavities in the median portion of the ski. Preferably, the series of recesses extends somewhat beyond the ends of the thickest portion 5. In the embodiment shown in the drawings, there is one groove 6 located in front of the thickened portion 5 whereas behind the thickened portion there are three grooves or recesses. It will be understood that the number of grooves may be varied. Moreover, the depth of the grooves is preferably graduated, the shallowest being situated at the end of the series and the deepest in the central portion. In cross-section, the grooves have a shape corresponding to a segment of a cylinder, the axis of which is disposed transversely with relation to the longitudinal axis of the ski (Fig. 4). As shown in Fig. 4, the space between successive grooves is approximately equal to the width of the grooves. This spacing may be varied. For example, the grooves may be closer together in the central portion of the series.

Forwardly and rearwardly of the series of recesses 6, the ski is reinforced by long, narrow, resilient steel strips 7 which are disposed in longitudinal channels of corresponding shape formed in the upper face of the intermediate layer 2. These metallic strips 7 preferably overlap two adjacent slats of the layers 1 and 2 so that the strips 7 reinforce the joint between the juxtaposed slats. As seen in Fig. 2, the metallic strips 7 extend from points near the thickened portion 5 almost to the forward and rearward ends of the ski. The ski is preferably also provided with steel edge strips 8 which extend substantially the full length of the ski.

The combination of the closed cavities 6 and

the resilient metallic strips 7 embedded between the layers of the ski has been found to give the ski great resilience without impairing its strength.

While the invention has been disclosed with reference to the preferred embodiment illustrated in the drawings, it will be understood that the construction may be modified within the scope of the appended claims. For example, the number of slats making up the respective superposed layers or pieces from which the ski is formed may be varied as desired. Moreover, instead of grooving all of the slats except the edge slats, as shown in Fig. 5, one or more intermediate slats may be left ungrooved so that the transverse grooves are not continuous. For example, with five slats, as shown in Fig. 5, the second and fourth slats only may be grooved, leaving the first, third and fifth slats ungrooved. Still other modifications within the scope of the present invention will be readily apparent to those skilled in the art.

What I claim and wish to secure by Letters Patent is:

1. A ski comprising at least two elongated pieces extending lengthwise of the ski and superposed on one another in the direction of the thickness of the ski, at least one of said pieces having in the median portion of its length a plurality of spaced recesses which have the shape of segments of cylinders and extend transversely of the ski but terminate at points spaced inwardly from the side edges of the ski, said pieces being secured together with the recesses in one piece facing the other piece and cooperating therewith to form completely enclosed cavities which give resilience to the ski.

2. A ski comprising at least two elongated pieces extending lengthwise of the ski and superposed on one another in the direction of the thickness of the ski, at least one of said pieces being a composite piece made up of not less than three strips comprising two side strips and an intermediate strip adhesively secured together, said intermediate strip having in the median portion of its length a plurality of spaced recesses which extend transversely of the ski but do not extend through said side strips, said pieces being secured together with the recesses in said composite piece facing the other piece and cooperating therewith to form completely enclosed cavities which give resilience to the ski.

3. A ski comprising at least two elongated pieces extending lengthwise of the ski and superposed on one another in the direction of the thickness of the ski, said pieces being adhesively secured together and at least one of them having its abutting face shaped to form a series of completely enclosed cavities between said pieces in the median portion of their length, said cavities extending transversely of the ski, and spaced elongated channels extending lengthwise of the ski forwardly and rearwardly of said series of transverse cavities and resilient metallic strips disposed in said channels.

4. A ski comprising at least two elongated pieces extending lengthwise of the ski and superposed on one another in the direction of the thickness of the ski, at least one of said pieces having a thickened section in the median portion of its length, the inner face of said thickened portion being provided with a series of spaced recesses which extend transversely of the ski but terminate at points spaced inwardly from the side edges of the ski, said pieces being secured together with the recesses in said piece facing the adjacent piece and cooperating therewith to form completely enclosed cavities which give resilience to the ski.

5. A ski according to claim 4, in which the series of cavities extends beyond the ends of said thickened portion.

6. A ski according to claim 4, in which the cavities are of graduated depth, being of lesser depth at the ends of the series and of greater depth intermediate the ends of the series.
